UNITED STATES PATENT OFFICE.

LOENDER C. EMERSON, OF NORTH GRAFTON, MASSACHUSETTS, ASSIGNOR
OF ONE-HALF TO CHARLES H. NELSON, OF SAME PLACE.

EYELETING-MACHINE.

SPECIFICATION forming part of Letters Patent No. 423,599, dated March 18, 1890.

Application filed March 19, 1889. Serial No. 303,862. (No model.)

To all whom it may concern:

Be it known that I, LOENDER C. EMERSON, of North Grafton, county of Worcester, State of Massachusetts, have invented an Improvement in Eyeletting-Machines, of which the following description, in connection with the accompanying drawings, is a specification, like letters and figures on the drawings representing like parts.

10 This invention has for its object to simplify the construction of eyeletting-machines, whereby they may be run at a faster speed than heretofore.

In my improved machine the work to be 15 eyeleted is laid right side up on a bed-plate, and the eyelet-hole is made by a punch which descends on the material and co-operates with a movable die-block or anvil at the under side of the material.

20 In my improved machine the punch on its way into the material enters the eyelet held in usual manner at the end of a raceway or other equivalent support, the punch passing through the eyelet.

25 The punch described is made longer than, and is arranged inside of, a hollow set, both the punch and the set having co-operating means, whereby they may be actuated independently each of the other. In this manner

30 after the punch has entered the eyelet and punched the material, the set, while the punch is yet in the eyelet, is moved to act upon the large end of the eyelet and drive it from the punch, while the latter acts as a guide, into

35 the hole previously made in the material by the said punch, the punch having in the meantime been partially raised, but preferably not far enough to lift it above the face of the material. The punch having been moved to

40 punch a hole in the material, as described, the die-block or anvil referred to is quickly turned aside, and the set co-operating with the one surrounding the punch is quickly raised into the position occupied by the an-

45 vil when the punch entered the material, and as herein provided for both sets are made to approach each other, and in so doing act to upset both ends of the eyelet. The punch is lifted from the eyelet just before the two sets

50 act to upset the eyelet.

Prior to my invention I am not aware that a punch has been made to reciprocate within a tubular set, both the punch and the set being actuated independently, and so, also, prior to my invention I am not aware that a 55 punch in deriving its movement toward the material to punch the same for the reception of the eyelet has ever been combined with means to support or hold and present the eyelet so that the punch might enter it on its way 60 to punch the material.

In my improved machine I have so constructed the eyelet-feeding mechanism that the eyelets are fed into the raceway constituting a support for them with their large 65 ends uppermost, and to enable this to be done unerringly I have extended into the eyelet-hopper one or more receiving branches, into which the eyelets can enter in only the right way, a brush or other usual sweep moving the 70 eyelets along the said receiver or receivers into the raceway. The raceway has imparted to it a longitudinal movement away from the punch just after the punch in its descent through the eyelet has entered the 75 material.

In other earlier machines the undermost set, made tubular, has contained a spring-pin, which, after the material has been acted upon by a punch to make a hole therein for the eyelet, has entered the eyelet at the end of a raceway just before the raceway was moved longitudinally, and the said pin has been pushed back into the lowermost set against the spring supporting it by the end of the uppermost set. 80

Figure 1 in front elevation shows an eyeletting-machine representing one form of my invention to be herein described, the down-turned front end of the work-support being broken out. Fig. 2 is a sectional detail of 90 the hopper and the upper end of the raceway and receiver; Fig. 3, a section of Fig. 2 in the line x . Fig. 4 is a detail showing three converging receivers leading to one raceway. Fig. 5 is a partial left-hand elevation of the machine shown in Fig. 1, the frame-work being partially broken out. Fig. 6 is a section of Fig. 5 in the dotted line x' ; and Fig. 7 is a detail looking upwardly from the dotted line x^2 , Fig. 1, chiefly to show an under side view 95 100

of the devices immediately below the said support, the arm g^5 and the link 12 being broken off.

The frame-work A is and may be of suitable shape to sustain the working parts.

The main shaft A', provided at one end with any usual form of driving-pulley, preferably some form of clutch-pulley under the control of a treadle, (not shown,) has on it two eccentric straps b^1 , a cam c , and a crank-pin d .

The eccentric-strap b' surrounding the eccentric b is represented as broadened and cut out at its upper end (see Fig. 5) to receive a spiral or other spring b^2 , through which is extended a threaded rod b^3 , upon which, below the lower end of the said spring, is applied a suitable nut, the upper end of the said rod being provided with an eye to embrace a suitable pin or stud b^4 of an arm b^5 fast on a rock-shaft b^6 , the said rod entering loosely the upper end of the said eccentric-link. The rock-shaft b^6 has a second arm b^7 , to which is connected a link b^8 , it, at its lower end, engaging a stud b^9 on the upright rod b^{10} of the carrier $b^{10} b^{12}$, to the forward end of which is secured by screw b^{13} the hollow or tubular upper set b^{14} . The spring b^2 enables the set b^{14} to yield to the thickness of the material.

The eccentric a is shown as surrounded by an eccentric-strap rod a' , which at its upper end is connected to a stud a^2 of an arm a^3 , fast on a rock-shaft a^4 , (shown only in Fig. 6,) the said shaft being parallel to the shaft b^6 , and having a second arm a^5 , to which is jointed a link a^6 , the lower end of the link being connected to a stud a^7 , projected from the rod a^8 , having at its upper end an arm a^{10} , to which is secured by a suitable set-screw, or in other usual manner, the punch p , the said punch being extended down through the hollow upper set b^{14} , the two eccentrics being so placed on the shaft A' as to move the said punch and upper set independently, the punch always remaining in the upper set, and, as herein represented, the lower reduced upper end of the punch is guided by the set. The rod a^8 is reciprocated in the guide-stand as a^9 . The crank-pin d is extended from a disk A², connected to or forming part of the main shaft A'. The crank-pin d receives a link d' , which at its lower end embraces a stud d^2 , shown as extended from a collar d^3 , secured to the lowermost set d^4 by a set-screw d^5 , the said set d^4 reciprocating in a post-like guide d^6 , secured rigidly to the frame-work. The upper end of the set d^4 is reduced, as seen in Fig. 5, to leave a small point to enter and remain in the eyelet after the latter has been discharged from the punch by the set b^{14} , the said point acting as usual to prevent the eyelet from being crushed while being set.

The hopper B, preferably a circular shell, having a feeder B¹⁶, is mounted on a carriage B⁷, having, as represented, a dovetailed foot B⁸, which is free to slide in a similar-shaped guideway of a block B⁹, secured to or forming part of a stand B¹⁰. The hopper contains a

wheel B², (shown as a brush,) it being fast to a shaft B', extended through the hopper and provided with a pinion B³, which is engaged by a toothed sector B⁴, pivoted on a stud B⁵, the said sector having connected to it a rod B⁶, which at its lower end is jointed to a stud or arm B⁷, fast to the rock-shaft a^4 , (see Fig. 6,) the said rock-shaft, through the devices described, oscillating the said wheel in the hopper, so as to sweep the eyelets 2 from the receivers f into the upper end of the groove of the raceway f' , the said raceway having at one side its central open groove a cover, as f^2 , to keep the eyelets large end up in the said groove. This raceway is secured to or forms part of an arm of the carriage B⁷, as best shown in Fig. 1. The raceway constituting a support for the eyelet to be entered by the punch and next to be set has at its lower end any usual form of detent, as 3, preferably some sort of a spring to keep the endmost eyelet of the row of eyelets in the raceway in place to be entered by the punch as it descends to punch a hole in the material lying on the table g , the said detent yielding, however, readily to permit the removal of an eyelet from the raceway or support after the same has been entered by the punch, the said raceway being at such time moved longitudinally away from the punch by a rock-shaft e^2 , one arm e' of which is connected loosely to a stud or projection e of the carriage B⁷, the said shaft having a second arm, as e^4 , one end of which is normally held by a spring 5 in the range of movement of a stud e^5 , extended from the arm b^{12} . The spring 5 is connected at one end to a stud of the carriage B⁷, and at its other end to a stud 6 of the guide B⁹. The rock-shaft e^2 has its bearing in a block e^8 at the upper end of a stand e^x , the said block, as shown, having sleeve-like extensions at each side.

The work-support g , supported rigidly on the frame-work, has a slot g' , in which reciprocates the serrated feed-bar g^2 and a small opening 7, in which stands and moves the anvil h when not in operative position. The support g has depending from it a guide g^3 , in which reciprocates the feed-carrying slide g^4 , it having extended from it the arm 8, to which is secured the feed-bar g^2 . The arm 8 has connected to it loosely a link 12, jointed at its other end by a stud 13 to one arm of a rocker-lever g^5 having a stud g^x , which takes a bearing in a sleeve 20, herein shown as fixed to the support g . The opposite arm of the said rocker-lever has jointed to it a link g^6 , in turn jointed at its other end to a lever 14, pivoted at 15 to the frame-work.

The lever 14 is shown as grooved at its inner side (see dotted lines) to receive a pin 16, extended from a regulating-block 17, adjustably connected, as by a set-screw 22, to a uniformly-vibrating arm 18 of a rock-shaft c' , having a second arm c^2 , provided with a roller or other usual stud c^3 , which enters the groove of the cam c . The elbow-lever g^5 in

its movements reciprocates the slide g^4 and actuates the feed-bar to move over the support g intermittently the material in which the eyelet is to be set, adjustment of the 5 block 17 providing different lengths of feed. The slide g^4 has at one side an extension, in which is placed a presser-bar 23, having in it a vertical passage for the reception of the said presser-bar, the latter having an arm 24, 10 the front of which is provided with a suitable presser-foot 25, to keep the material down on the feed-bar and the support g , the said presser being acted upon by a suitable spring, as 26, (see Fig. 5,) which normally keeps the 15 presser-foot pressed down.

The presser-foot, it will be understood, will move forward in unison with the feed-bar; but when the feed-bar is being moved backwardly the presser-foot is elevated from the 20 material by, as herein shown, a lever m , pivoted at 29 on the bar g^3 , the said lever being connected by a rod 30 to a stud 31 of a lever m^2 , having its fulcrum at m^3 and provided with a roll 34, which in the rotation of the 25 shaft A' is struck by a cam 35, forming part of the disk d . The lower end of the rod 23 has a roller 28, which obviates friction between the bar and the lever m .

The support g has pivoted to it at 40 one 30 end of the lever 42, which at or near its other end has attached to it the punch-block or anvil h , the said lever being slotted to receive a roller or other stud 43 of an arm 44, extended from the slide g^4 , the movements of 35 the said slide, when operating to effect the forward or feeding motion of the material, acting through the stud 43 to vibrate the lever 42 and place the die-block or anvil in position immediately in the path of movement 40 of the punch p , the lower set d^4 being then down, as in Fig. 5.

During the feeding movement of the material the punch p commences to descend, and in its descent enters the large upper end of 45 the eyelet at the lower end of the raceway or support, the said punch continuing its descent and meeting the material just as the feeding-stroke is completed, the punch striking the material immediately above the 50 punch-block or anvil and making the usual hole for the eyelet. The hole having been made, the punch is raised slightly (in practice about one-sixteenth of an inch) to relieve the punch from the punch-block, and then the 55 feed starts back quickly, the slide g^4 in its backward movement (the foot being then lifted, as described) acting, as described, to swing the lever 42 aside and remove the die-block or anvil from under the punch. As the 60 die-block moves away from under the punch, the crank-pin d acts to lift the set d^4 until the point at its upper end enters the eyelet, and the shoulder next the said projection meets the end of the eyelet then in the material 65 and surrounding the punch p , the said eyelet having been pushed down along the said punch and into the material surrounding it

by the upper set b^4 , it having been actuated and moved downwardly, but not until just after the raceway was pulled or moved backwardly far enough to retire from the eyelet then on the punch, the downward movement of the set b^4 after the removal of the eyelet from the raceway pushing the eyelet into the material. The movements of the two sets b^4 70 and d^4 are preferably such that after each comes in contact with opposite ends of the eyelet both of the said sets have sufficient movement one toward the other to upset the eyelet in usual manner, the punch retiring 75 from the eyelet just before the latter is fully upset.

It will be noticed that the receivers extend into and partially surround the brush B^2 . The grooves in the receivers (see Fig. 3) are 80 narrower at their lower than at their upper parts, so that the eyelets can enter therein only with their small ends down, the brush in its movement in the direction of the arrow, Fig. 2, acting to sweep the eyelets lodged 85 in the said receivers into the raceway, down which they slide. The brush in its backward movement brushes from the tops of the receivers any loose eyelets therein and not properly entering the grooves of the receivers. 90

I do not desire to limit my invention to the exact form of hopper or brush, nor to the exact form of feeding mechanism; but instead may use any other well-known equivalent devices. 100

I claim—

1. In an eyeleting-machine, the combination, with a support for the eyelet to be set, of a tubular set, means to reciprocate it, the punch extended therethrough, and means to positively actuate it independently of the said set, and a punch-block or anvil, the combination being and operating substantially as described. 110

2. In an eyeleting-machine, the combination, with a support for the eyelet to be set, of a tubular set, and an independent punch therein, means to reciprocate it, and a punch-block or anvil, of an opposing set, and means to reciprocate it to co-operate with the said tubular set, to operate substantially as described. 115

3. In an eyelet-setting machine, the following instrumentalities, viz: a raceway or support for the eyelets to be set, a table on which the material rests, a punch to enter the eyelet in the said support and in its further movement in the same direction punch a hole in the material, a die-block or anvil co-operating with the punch, a tubular set surrounding the said punch, an opposing set, as d^4 , means to move the said die-block or anvil into and out of operative position with relation to the said punch, and independent means to reciprocate the said punch and the set surrounding it to operate substantially as described. 125

4. In an eyelet-setting machine, the following instrumentalities, viz: a raceway or sup-

port for the eyelets to be set, a support for the material, a punch to enter the eyelet during a portion of its descent and in its further descent to punch a hole in the material, a 5 die-block or anvil co-operating with the punch, a tubular set surrounding the punch, an opposing set, as d^4 , means to move the said die-block or anvil into and out of operative position with relation to the punch, and 10 means to reciprocate the said punch and the said set surrounding it independently, and feeding mechanism to feed the material, substantially as described.

5. In an eyeleting-machine, the raceway for 15 the eyelet to be set, the said raceway having

a groove shaped, as described, to admit the eyelet only with its small end down, the support at the end of the said raceway for the said eyelet, a detent or stop at the end of the raceway, and a hollow top set, combined with 20 an independent punch movable in the said hollow set, and a punch-block or anvil to operate substantially as described.

In testimony whereof I have signed my name to this specification in the presence of 25 two subscribing witnesses.

LOENDER C. EMERSON.
